US0D1046842S

(12) **United States Design Patent** (10) **Patent No.:** **US D1,046,842 S**
(45) **Date of Patent:** **** Oct. 15, 2024**

(54) **COMPUTER**

(71) Applicant: **Siemens Aktiengesellschaft**, Munich (DE)

(72) Inventors: **Shi Kong Lin**, Chengdu (CN); **Xue Kang Li**, Chengdu (CN); **Ting Lai**, Chengdu (CN)

(73) Assignee: **SIEMENS AKTIENGESELLSCHAFT**, Munich (DE)

(**) Term: **15 Years**

(21) Appl. No.: **29/832,069**

(22) Filed: **Mar. 24, 2022**

(30) **Foreign Application Priority Data**

Sep. 28, 2021 (CN) 202130646055.0

(51) **LOC (14) Cl.** **14-02**

(52) **U.S. Cl.**

USPC **D14/301**; D13/179

(58) **Field of Classification Search**

USPC D14/140.2–140.4, 300–302, 308–309, D14/311–314, 348–349, 351, 353–358, D14/432–434, 439; D13/179

(57) **CLAIM**

The ornamental design for a computer, as shown and described.

DESCRIPTION

FIG. 1 is a front elevational view of a computer showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front, top and right-side perspective view thereof; and,

FIG. 8 is a rear, top and left-side perspective view thereof. The broken lines in the drawings illustrate portions of the computer that form no part of the claimed design.

1 Claim, 8 Drawing Sheets
